ICE CREEPER

Raymond C. Rupp, Kendallville, Ind.

Application September 18, 1939, Serial No. 295,507

5 Claims. (Cl. 36—62)

The invention aims to provide a simple, inexpensive and efficient ice creeper which may be quickly and easily applied and removed.

A further object is to provide one form of the invention particularly adapted for use when wearing overshoes, galoshes or the like.

Another object of the invention is to provide an additional form of construction particularly adapted for use when not wearing overshoes or the like.

With the foregoing in view, the invention resides in the novel subject matter hereinafter described and claimed, description being accomplished by reference to the accompanying drawing.

Figure 1 is a side elevation showing one form of the invention engaged with an overshoe.

Figure 2 is a perspective view of the device shown in Figure 1.

Figures 3 and 4 are perspective views showing a different form of construction to be engaged with an ordinary shoe sole.

In the form of construction shown in Figs. 1 and 2, a horizontally elongated metal plate 10 is provided, said plate having two calks 11 at each end and a notch or slot 12 between said calks. Two elongated loops 13 lie against the lower side of the plate 10 at the ends thereof and are adjustably secured thereto by bolts 14, the outer ends of said loops being curved upwardly at 15 through the notches or slots 12 and then extended forwardly and rearwardly to provide front arms 16 and rear arms 17. The plate 10 is to be positioned under the instep of the foot, 35 the arms 16 engage the sole edge of an overshoe, and the arms 17 engage the heel edge of said overshoe, said arms being preferably provided with covering sleeves 18 of rubber or the like to prevent them from injuring the shoe. In forming the loops 13 and arms 16—17, two lengths of 40 spring wire are used, one length being utilized for the loop and arms at one end of the plate 10, and the other for the loop and arms at the other end of said plate. The arms yieldably grip 45 the sole and heel edges and firmly hold the device in place, yet permit said device to be easily pulled from the overshoe when desired. Moreover, the resiliency of the arms permits easy application of the device without disturbing the 50 bolts 14, these bolts and the loops 13 being provided only to permit relative adjustment of the two sets of arms according to the width of the overshoe to be engaged.

In the form of construction shown in Figs. 3 and 4, a plate 10' is provided with calks 11' at its

ends, and one end of said plate is formed with a notch or slot 12' between the calks. A zig-zag spring 19 lies against the lower side of the plate 10' and is extended at one end as shown at 20 and bent upwardly and inwardly through the slot 12' to provide a hook 21 to engage one edge of a shoe sole, preferably directly in front of the heel. At the opposite end of the plate 10', another hook 22 is provided, said hook being preferably formed on a metal strip 23 which extends transversely of said plate, the ends of said strip being provided with flanges 24 clinched around the plate to hold the strip in position.

The end of the spring 19 remote from the hook 21 is provided with an elongated loop 25 through 15 which a bolt 26 passes to secure the spring to the plate 10'. Loosening of the bolt permits adjustment of the hook 21 toward or from the hook 22 according to the width of the shoe upon which the device is to be worn.

The form of construction last described, like the first-described form, may be quickly and easily attached or detached, and will be efficient and desirable.

While preferred details have been disclosed, 25 variations may of course be made within the scope of the invention as claimed.

I claim:

1. An ice creeper comprising an elongated plate to extend transversely of a shoe sole, the ends of 30 said plate being each provided with two calks, one end of said plate being formed with a notch between its calks, a shoe-sole-engaging-member extending through said notch and having an elongated loop lying against and disposed longitudinally of the lower side of said plate, a bolt passing through said loop and securing said member adjustably to said plate, and a second shoe-sole-engaging member connected with the end of said plate remote from said notch.

2. An ice creeper comprising a calk-carrying plate to extend transversely under the instep portion of an overshoe, upwardly and forwardly projecting spring arms on the ends of said plate to engage the sole edge of the overshoe, and upwardly and rearwardly projecting spring arms on 45 said ends of said plate to engage the heel edge of the overshoe.

3. A structure as specified in claim 2; together with an elongated loop connecting said front and rear arms at least at one end of said plate and lying against said plate, and a bolt passing through said loop and securing the same to said plate for adjustment toward and from the arms at the other end of said plate.

4. An ice creeper comprising a calk-carrying plate to underlie a shoe sole, one end of said plate being provided with a slot, a hook on the other end of said plate to engage one edge of a
5 shoe sole, and a spring under said plate and secured at one of its ends thereto, the other end of said spring being bent upwardly through said slot and bent to provide a second hook to engage the other edge of the shoe sole.

5. A structure as specified in claim 4; said one end of said spring being bent to provide an elongated loop, and a bolt passing through said loop and adjustably securing said spring to said plate.
